UNITED STATES PATENT OFFICE.

JOSEPH KAUFMAN, OF NEW YORK, N. Y.

SAFETY-RAZOR-BLADE PACKAGE.

932,137.

Specification of Letters Patent. Patented Aug. 24, 1909.

Application filed July 27, 1907, Serial No. 385,846. Renewed January 25, 1909. Serial No. 474,155.

To all whom it may concern:

Be it known that I, JOSEPH KAUFMAN, a citizen of the United States, and a resident of New York city, in the county of New 5 York and State of New York, have invented certain new and useful Improvements in Safety-Razor-Blade Packages, of which the following is a specification.

This invention relates to safety razor blade packages and the object of my invention is to provide a new and improved package in which the blade is held in such a manner that its cutting edge cannot be injured or drilled, is fully protected and the entire 15 blade is securely protected from the influences of moisture and is thus protected from the influences of rust or other oxidation and persons handling packages containing the blades are not apt to cut themselves or to 20 mar, injure or deface the cutting edge of the blade while handling the packages.

In the accompanying drawings, in which like letters of reference indicate like parts in all the figures: Figure 1 is a perspective view 25 of the blade and the receiving slip, detached. Fig. 2 is a cross sectional view through the blade and the receiving slip. Fig. 3 is a face view of the blade and receiving slip in the waxed paper envelop. Fig. 4 is a perspective view of the completed package. Fig. 5 is a central transverse sectional view through the completed package, exaggerated.

The safety razor blade A has a thickened back B forming a longitudinal shoulder C 35 on each side face of the blade. The blade is inserted in a flattened paper slip D of just sufficient length to receive the blade and of such width that when the shoulders C of the blade rest upon the upper edges of the 40 slip D the cutting edge of the blade will be held about one eighth of an inch, more or less, from the opposite open edge of the slip and this cutting edge is thus, by the edges of the paper slip protected from injury even if 45 the slip is placed forcibly on its bottom

edges, and in fact quite a heavy blow on the bottom edges of the slip cannot injure the cutting edge of the blade. The slip D is formed of fairly heavy paper, folded over so that the edges overlap, which overlapping 50 edges may be united by an adhesive substance. The slip is open at the top and bottom but closed at the ends and to apply the slip it is only necessary to insert the blade until its shoulders rest upon the edges of 55 one longitudinal opening of the slip. The slip with the blade therein is then placed into a waxed paper envelop F, the edges and ends of which are folded over the blade and slip and then a sealing and retaining band G 60 is placed around the envelop.

I am aware that various types of metal blade retainers or receptacles have been devised for holding safety razor blades until they are required and I am also aware that 65 safety razor blades have been packed in paper envelops of various kinds.

Having described my invention what I claim as new and desire to secure by Letters Patent is:—

The combination with a safety razor blade having longitudinal shoulders, of a paper slip of much greater length than width and open at the top and having closed ends, the blade being inserted into the slip, 75 the shoulders of the blade resting on the upper edges of the slip and the cutting edge of the blade being a short distance inward from the bottom edge of the slip, and an envelop surrounding the blade and slip, and 80 a retaining and sealing band surrounding the envelop, substantially as set forth.

Signed at New York city in the county of New York and State of New York this 10th day of July A. D. 1907.

JOSEPH KAUFMAN.
